Hampden, Mass. 01036

Primary Examiner—Paula A. Mortimer
Attorney, Agent, or Firm—McCormick, Paulting & Huber

[**] Term: **14 Years**

[57] **CLAIM**

[21] Appl. No.: **58,030**

The ornamental design for a shoulder strap for retaining
pocketbook straps, as shown and described.

[22] Filed: **Aug. 6, 1996**

DESCRIPTION

[51] LOC (6) Cl. **02-07**

FIG. 1 is a front perspective view of a shoulder strap for
retaining pocketbook straps showing my new design;

[52] U.S. Cl. **D2/624; D3/327**

FIG. 2 is an enlarged top plan view thereof;

[58] **Field of Search** D2/624, 626, 627,

FIG. 3 is a side elevational view thereof, the opposite side
is a mirror image;

D2/639; D3/201, 215, 218, 224, 226, 228,

FIG. 4 is a bottom view thereof; and,

230, 318, 327, 328; 190/DIG. 110; 2/300,

FIG. 5 is an end elevational view thereof, the opposite end
is a mirror image.

311, 10, 230, 235, 236

The broken line showing of the human form and strap in
FIG. 1 is for illustrative purposes only and forms no part of
the claimed design.
